Attorney

UNITED STATES PATENT OFFICE.

NORMAN C. KOHR, OF COLUMBUS, OHIO, ASSIGNOR TO ELECTRIC AUTO-LITE CORPORATION, OF TOLEDO, OHIO, A CORPORATION OF DELAWARE.

TRANSMISSION-GEARING.

1,360,171.

Specification of Letters Patent. Patented Nov. 23, 1920.

Application filed March 16, 1918. Serial No. 222,863.

To all whom it may concern:

Be it known that I, NORMAN C. KOHR, a citizen of the United States, residing at Columbus, in the county of Franklin and State of Ohio, have invented certain new and useful Improvements in Transmission-Gearing, of which I declare the following to be a full, clear, and exact description.

This invention relates to transmission gearing as employed with electric motors for starting internal combustion engines.

The principal object of this invention is to provide a novel and effective interconnecting gear between the starting motor and engine fly-wheel which will mesh and unmesh automatically and without serious jar to the movable parts.

Further objects, and objects relating to economies of manufacture and details of construction will definitely appear from the detailed description to follow.

I accomplish the objects of this invention by the devices described in the following specification.

25 A structure constituting a preferred embodiment of my invention is illustrated in the accompanying drawings, forming a part of this specification, in which:—

Figure I is a sectional view through a starting motor showing the gear in disengaged position;

Fig. II is a similar view with the motor casing removed showing the gear in engagement;

35 Fig. III is a detail view taken on the line III—III of Fig. I; and

Fig. IV is a detail view taken on line IV—IV of Fig. I.

In the drawings, similar reference numerals refer to similar parts throughout the several views, and the sectional views are taken looking in the direction of the arrows at the ends of the section lines.

As illustrated in the drawings, I employ a usual form of starting motor which includes a casing 1, field 2 and armature 3, which latter is mounted on the shaft 4, having a bearing at both ends in the casing, as at 5 and 6. The shaft 4 is hollow, and adjacent one end has an internal thread 7, with which is meshed a secondary or stub shaft 8, having an externally threaded portion 9. One end of the shaft 8 bears a pinion 10 which is weighted on one side as at 11, for a purpose hereinafter described.

This pinion 10 is adapted for engagement with gear teeth 12, cut on the fly-wheel 13 of the engine, and is keyed to the secondary shaft.

The end of the secondary shaft opposite 60 that which bears the pinion 10 has attached to it a cap 14, and adjacent this cap and encircling the secondary shaft is a spiral compression spring 15. A buffer ring 16 lies next to the spring 15, as shown. 65

Mounted on one end of the shaft 4, and adapted for slidable movement thereon, is a cap 17, having cylindrical walls and an end piece 18 apertured to receive the secondary shaft. Within this cap and bearing 70 on the end of the main shaft, is a compression spring 19.

The secondary shaft has axial movement relative to the armature shaft by virtue of its screw threaded relationship therewith. 75 It is limited in its outward movement by engagement of the buffer ring 16 against the outstanding internal screw thread at 20, and in its inner movement by the engagement of the pinion and the buffer cap 17. 80

The normal inactive position of the gearing as is shown in Fig. I. When the motor is started and the armature begins to rotate, the inertia of the pinion will tend to hold it from rotative movement, thereby causing 85 the secondary shaft to move inwardly on its screw thread. This inward movement of the stub shaft brings the pinion into mesh with the fly-wheel gear and is continued until the pinion bears against the buffer cap. 90

The load of the engine shaft then becomes effective and as the buffer spring is being compressed, the fly-wheel is gradually accelerated up to armature speed without any serious jarring effects. As soon as the engine starts up under its own power, the fly-wheel speed is greatly accelerated, resulting in a relatively greater rotative speed in the secondary shaft than in the armature shaft. The difference in speed relationship causes the secondary shaft to screw outwardly from the main shaft until the buffer ring engages the screw thread terminal, when the pinion will be in complete disengagement from the fly-wheel. 100

I am aware that the particular embodiment of my invention, here shown and described, is susceptible of considerable variation without departing from the spirit of my invention, and, therefore, I desire to claim 110

the same broadly as well as specifically as indicated by the appended claims.

Having thus described my invention, what I claim as new, and desire to secure by Letters Patent, is:—

1. In a starting system for an internal combustion engine having a gear wheel, a driving shaft, a driven shaft screw-threaded thereto, a pinion, secured to said driven shaft and adapted upon initial rotation of said driving shaft to move longitudinally into mesh with said gear wheel, a buffer spring surrounding said driven shaft between said pinion and said driving shaft, and a closely fitting protective cap for said spring mounted on the end of said driving shaft.
2. In a starting system for an internal combustion engine having a gear wheel, a hollow driving shaft, a driven shaft, screw-threaded thereinto, a pinion secured to one end of said driven shaft and adapted upon initial rotation of said driving shaft to move longitudinally thereof into meshing engagement with said gear wheel, and a compression spring within said hollow driving shaft and adapted to coöperate therewith and with an end portion of said driven shaft to limit the movement of said pinion when moving out of engagement with said gear wheel.
3. In a starting system for an internal combustion engine having a gear wheel, a hollow driving shaft, a driven shaft screw-threaded thereinto, a pinion secured to one end of said driven shaft and adapted upon initial rotation of said driving shaft to move toward the same into meshing engagement with said gear wheel and a compression spring within said hollow driving shaft for

limiting the outward movement of said pinion and driven shaft upon disengagement of the former from said gear wheel.

4. In a starting system for an internal combustion engine having a gear wheel, a hollow driving shaft upon which the rotatable element of a driving motor is adapted to be mounted, said shaft having a screw threaded portion, a screw threaded shaft engaging said driving shaft, a pinion secured to said driven shaft adapted to move toward said hollow driving shaft to engage said gear and to move away from the same to disengage the said gear and cushioning means within said hollow driving shaft for limiting the outward disengaging movement of said pinion.

5. In a starting system for an internal combustion engine having a gear wheel, the combination of a hollow driving shaft, a driven shaft screw-threaded thereinto, a pinion secured to one end of said driven shaft and adapted upon initial rotation of said driving shaft to move longitudinally thereof into meshing engagement with said gear wheel, a buffer spring surrounding said driven shaft, between said pinion and said driving shaft, a closely fitting protective cap for said spring mounted on the end of said driving shaft, and a compression spring within said hollow driving shaft and adapted to coöperate therewith and with an end portion of said driven shaft to limit the movement of said pinion when moving out of engagement with said gear wheel.

In testimony whereof, I affix my signature.

NORMAN C. KOHR.
